UNITED STATES PATENT OFFICE.

PHILIP L. MCKEE, OF CHICAGO, ILLINOIS.

ROOF STRUCTURE.

Application filed September 17, 1925. Serial No. 56,887.

To all whom it may concern:

Be it known that I, PHILIP L. MCKEE, a citizen of the United States, residing at Chicago, in the county of Cook and State of Illinois, have invented a certain new and useful Improvement in Roof Structures, of which the following is a specification.

My invention relates to roof structures, especially for greenhouses and the like, in which there are wooden rafters or sash bars supported upon purlins or other suitable transverse supports. It will be understood that in greenhouses, especially, there is a high percentage of moisture in the atmosphere which tends to promote decay of the rafters and other parts of the building and contents. To retard decay, cypress or other moisture resisting wood is usually employed, but even with this precaution there is apt to be rapid decay where the wood receives screws or other fastening devices by which the parts of the buildings are held together. One of the objects of my invention is to provide fastening means for holding the sash bar to its purlins, so designed as to reduce the tendency of water to collect or remain at the points where the fastening devices are located.

It will also be understood that according to modern practice the sash bars, purlins and other component parts of a greenhouse are factory made, with the result that when the parts come to be assembled in the field there is sometimes a slight discrepancy in dimensions, thus making it difficult at times to fit the parts together. One of the objects of my invention is to compensate for this and to provide fastening means so designed that ordinary inaccuracies may be absorbed and the parts may be assembled and drawn together without requiring any hand fitting or cutting of the parts.

I accomplish my objects by the construction illustrated in the accompanying drawings in which

Figure 1 is an assembly view showing a portion of the roof of a greenhouse including a rafter or sash bar, a purlin, and the means which I have provided for fastening the two together.

Figure 2 is a sectional elevation on the line 2—2 Figure 1.

Figure 3 is a plan section on the line 3—3 Figure 4.

Figure 4 is a sectional elevation on the line 4—4 Figure 2.

Figure 5 is a side view of a modified form of eye bolt or fastening stud.

Like numerals denote like parts throughout the several views.

In the form shown in the drawings the ridge pole 1 has a cap 2 which supports hinges 3. These hinges are fastened to and secure sash frames 4 provided with panes 6 of glass. These elements are not particularly concerned with the principle of my invention and may be greatly varied in design.

The building is provided in the usual manner with purlins 8 which run parallel to the ridge pole. In the form illustrated the purlins are angle bars, the upper legs of which are inclined at the same angle as the rafters or sash bars 10. I have shown a conventional design of sash bar, the same having shoulders 12 for supporting the stationary pane 14 of glass. They are also provided with the usual gutters 16 for carrying off the water of condensation.

Referring now to the parts more intimately concerned with my invention, the sash bar has a chamber 18 formed in the under side and a pin 20 passes transversely through it, and through the sash bar. The pin may assume different forms but in the form illustrated is like a stove bolt, the threaded end of which screws into a nut 22 which is countersunk in the side of the rafter as best shown in Figure 2. Thus the pin is firmly supported in the rafter.

An eye bolt 24 is supported upon pin 20, the pin passing through the eye of the bolt. This bolt may have an elongated or slotted head as shown in Figure 4 or may assume the form of the eye bolt 27 shown in Figure 5, in which the eye is circular. The threaded shank of this eye bolt or stud passes through an aperture 26 formed in the upper leg of the purlin. A nut 28 screws onto the lower end of the eye bolt and serves to draw down the eye bolt toward the purlin, thus firmly clamping the parts together. If desired a washer 30 may be interposed between the bottom of the rafter and the top of the purlin for the purpose of draining. This holds the parts separated and prevents the water from collecting and remaining at the point where the rafter seats upon the purlin.

In practice, with the parts designed as shown and described there is little or no tendency for water to collect at the point where the sash bar is fastened to the purlin. In fact water readily drains away, thus keep-

ing the wood reasonably dry and retarding decay. Another advantage of this construction is that it affords considerable play, especially as it is usual to make the aperture 26 somewhat larger than the diameter of the shank of the eye bolt or stud. As a result of this construction, whether the eye of the stud is elongated or not, the parts will come together readily because if they do not at 10 first come into juxtaposition the stud may be inserted at various angles through the aperture 26, after which the nut 28 may be tightened, which will tend to draw the parts firmly together and bring them into adjusted relation.

It will be observed that the construction is simple and requires only two principal parts, viz, the cross pin 20 and the eye bolt 24. Both of these elements may be of standard construction and hence purchasable in the open market.

Having thus described my invention what I claim as new and desire to secure by Letters Patent is:

25 1. In a roof structure for greenhouses and the like, a purlin, a sash bar having a chamber in the under side, a pin passing transversely through the chamber and supported in the sash bar, and a fastening element 30 extending into said chamber and supported by the pin and engaging the purlin for holding the parts together.

2. In a roof structure for greenhouses and the like, a purlin, a sash bar having a chamber in the under side, a pin passing transversely through said chamber and supported in the sash bar, and a fastening element ex-

tending into said chamber and loosely mounted on the pin and having a clamping engagement with the purlin for holding 40 the parts together.

3. In a roof structure for greenhouses and the like, a purlin having an aperture in it, a sash bar having a chamber in the under side, a pin passing transversely 45 through said chamber and supported in the sash bar, an eye bolt passing through the aperture in the purlin, the eye of said bolt encircling the pin within the chamber, and means screwing on the eye bolt for clamping 50 the purlin to the sash bar.

4. In a roof structure for greenhouses and the like, a purlin, a sash bar having a chamber in the under side, a pin passing transversely through said chamber and supported 55 in the sash bar, an eye bolt having an elongated eye enclosing the pin for being supported thereby, and means acting upon the eye bolt and purlin for drawing the eye bolt and sash bar toward the purlin for holding the parts together.

5. In a roof structure for greenhouses and the like, an inclined sash bar, a purlin located beneath the same for supporting it and having the supporting surface arranged at the 65 same angle of inclination as the sash bar, a fastening device secured to the sash bar and penetrating the purlin, and a washer surrounding the fastening device and interposed between the purlin and sash bar for 70 spacing them apart and promoting drainage.

In witness whereof, I have hereunto subscribed my name.

PHILIP L. MCKEE.
